Inventor,
Carl O. Anderson,
Wilbur M. Stone,
By his Attorney

UNITED STATES PATENT OFFICE.

CARL O. ANDERSON, OF BROOKLYN, NEW YORK.

PLIERS.

Application filed June 13, 1922. Serial No. 567,918.

To all whom it may concern:

Be it known that I, CARL O. ANDERSON, a citizen of the United States, and a resident of New York, borough of Brooklyn, in the county of Kings and State of New York, have invented certain new and useful Improvements in Pliers, of which the following is a specification.

This invention relates to pliers, and one object of my improvements is to provide a tool of the character specified wherein the fulcrum between the two members of the tool is shifted during the use of the tool. Other objects will appear later herein.

As one embodiment of the invention, my improved pliers are illustrated in the drawing accompanying this specification as particularly adapted for use as a cotter pin puller. In its illustrated form, which may be the preferred embodiment of my improvements, said pliers are also efficient for pulling staples and for removing and expanding piston rings. Other uses will be obvious to those skilled in the art.

Figure 1 of the drawing is a side elevation, partly in section, of my improved pliers as applied to the removal of a cotter pin. Fig. 2 is a fragmentary elevation similar to that of Fig. 1 showing a succeeding step in the operation of the tool. Figs. 3 and 4 are fragmentary side elevations, respectively, showing further steps in the operation of said tool. Fig. 5 is a front elevation corresponding with Fig. 3. All the views are to one scale.

For purposes of economic manufacture my improved pliers are preferably made up of sheet metal, such as steel, the lower arm 2 being of U shaped cross section and terminating at its operative end in work engaging means such as opposite feet 3, 3. The rear or handle end of arm 2 may be of blade-like formation, as at 2^b, to serve as a screw driver, lever, or the like. The handle portion 4 of upper arm 10 is also preferably of U shaped cross section, and to that portion thereof nearest feet 3, 3 of arm 2 is fixed nose piece 5, preferably by riveting between side walls 4^a, 4^a, thereof. Said nose piece 5 terminates at its operative end in a work engaging horn or nose 5^a, projecting slightly beyond feet 3, 3 of arm 2 and adapted for entering the eye, as 6^a, of a cotter pin 6.

The following means are provided for connecting arms 2 and 10: A short distance backwardly from said nose 5^a, member 5 is

provided with an opening 7, preferably in the form of a transverse slot, through which passes fulcrum pin 8 secured in the opposite walls of arm 2. The lower edges of side walls 4^a, 4^a of member 4, curve upwardly at their forward ends, respectively, whereby opposite cams are formed, and the upper edges of side walls 2^a, 2^a of arm 2 are inclined downwardly from near fulcrum 8 toward handle end 2^b, forming tracks for said cams, whereby coacting rolling seats are provided on said members 2 and 4, for purposes more fully set forth in the description of the operation of my improved pliers.

The operation of my improved pliers is as follows: The handle ends of arms 2 and 10 being separated as far as may be, see Fig. 1, the lower portion of slot 7 engages pin 8 whereby horn 5^a is depressed to the level of, or below, the points of feet 3, 3, thereby permitting the entrance of said horn within the eye 6^a of the low-lying head of cotter pin 6. If now handle 10 be depressed toward handle 2, pin 8 will presently be engaged by the upper end of slot 7 as a fulcrum, Fig. 2, whereby cotter pin 6 will be started from its seat under maximum leverage. Upon further depression of handle 10, cams 4^a engage their respective tracks 2^a, first, just above pin 8, Fig. 2, then rolling down said tracks at X, Fig. 3, and later at Y, Fig. 4, slot 7 permitting said movement of member 5 relative to pin 8. It will be observed that said movement of handle 10 relatively to handle 2, throws the fulcrum point constantly backward to the left, thereby decreasing the leverage for lifting pin 6, but constantly increasing the movement of nose 5^a from feet 3, 3, relatively to the movement of handle 10. Thus, at the commencement of the operation, when pin 6 is firmly seated, maximum leverage is had and, after the pin is started from its seat, that leverage decreases and the speed and stroke of lifting is correspondingly increased, thereby providing a very efficient action.

I claim:

1. A tool of the character described including in combination an upper arm and a lower arm, each of said arms having work engaging means, said arms being connected by means of a pivot pin carried by one of said arms and a transverse slot in the other arm through which said pin passes, a downwardly facing cam on said upper arm and

an upwardly facing track on said lower arm for engagement by said cam, the upper end of said slot at one time engaging said pin as a fulcrum and at another time said fulcrum lying between said cam and track.

2. A tool of the character described including in combination an upper arm and a lower arm, each of said arms having work engaging means, said arms being connected 10 by means of a pivot pin carried by one of said arms and a transverse slot in the other arm through which said pin passes, a downwardly facing cam on said upper arm and an upwardly facing track on said lower arm for engagement by said cam, the upper end of said slot at one time engaging said pin as a fulcrum, whereby during one part of the 15 operation of said tool the fulcrum of said arms is on said pivot pin and later is shifted 20 rearwardly therefrom to between said cam and track.

3. A tool of the character described including in combination an upper arm and a lower arm, each of said arms having work 25 engaging means, said arms being connected by means of a pivot pin carried by one of said arms and a transverse slot in the other arm through which said pin passes, a downwardly facing cam on said upper arm and

an upwardly facing track on said lower arm for engagement by said cam, whereby in operation the lower portion of said slot first engages said pivot pin, then the upper end of said slot engages said pin as a fulcrum and later the fulcrum of said arms is shifted 35 rearwardly from said pin to between said cam and track.

4. In a tool of the character described the combination of an upper arm and a lower arm, each of said arms having work engaging 40 means, a pivot pin carried by one arm and passing through a transverse slot in the other arm, and means on said arms operable to vary the degree of leverage applied to said work engaging means while the tool is in 45 operation.

5. In a tool of the character described the combination of an upper arm and a lower arm, each of said arms having work engaging means, a pivot pin carried by one arm 50 and passing through a transverse slot in the other arm, and means on said arms operable to shift the point of fulcrum relatively to said work engaging means while the tool is in operation.

In witness whereof, I hereby affix my signature, this 9th day of June, 1922.

CARL O. ANDERSON.
